US0D1108088S

(12) **United States Design Patent** (10) **Patent No.:** **US D1,108,088 S**
(45) **Date of Patent:** **** Jan. 6, 2026**

(54) **HEADWEAR**

(71) Applicant: **Leliyma Corporate SRL**, Milan (IT)

(72) Inventor: **Emanuele Danzi**, Riccione (IT)

(**) Term: **15 Years**

(21) Appl. No.: **35/522,202**

(22) Filed: **Aug. 8, 2024**

(80) **Hague Agreement Data**

Int. Filing Date: **Aug. 8, 2024**

Int. Reg. No.: **DM/239675**

Int. Reg. Date: **Aug. 8, 2024**

Int. Reg. Pub. Date: **Sep. 6, 2024**

(57) **CLAIM**

The ornamental design for headwear as shown and described.

DESCRIPTION

FIG. 1.1 is a front elevational view of the headwear;

FIG. 1.2 is a left side elevational view thereof, the right side being a mirror image thereof; and

FIG. 1.3 is a back elevational view thereof.

The structural features depicted by broken lines in the drawings have been shown for the purpose of illustrating portions of the headwear that form no part of the claimed design.
